UNITED STATES PATENT OFFICE.

HAROLD G. BOWKER, OF CLINTONVILLE, WISCONSIN, ASSIGNOR TO TOPP-STEWART TRACTOR CO., OF CLINTONVILLE, WISCONSIN.

TRACTOR LAG.

Application filed April 15, 1921. Serial No. 461,523.

To all whom it may concern:

Be it known that I, HAROLD G. BOWKER, a citizen of the United States, and resident of Clintonville, in the county of Waupaca 5 and State of Wisconsin, have invented certain new and useful Improvements in Tractor Lags; and I do hereby declare that the following is a full, clear, and exact description thereof.

10 My invention relates to new and useful improvements in tractor lags, such as are designed to engage the ground surface over which the tractor is propelled, and to form an automatic movable track on which the 15 wheel tread movably rests.

Lags of this type hitherto have been usually suspended from the inside of the rim by relief pins which extend over the edges of the tire and thus cause considerable wear 20 thereon, due to side thrust.

One important object of my invention is to provide a lag which shall be suspended directly from the flanged member, which forms the bearing surface for the wheel to 25 which it is attached.

Another object of the invention is to so construct the contacting surfaces of the flanged member and lag, that there will be a true rolling action between them, whereby 30 a minimum amount of wear occurs, and the life of the lag member is thereby lengthened.

With the above and other objects in view, my invention consists of the structural details herein described in connection with the 35 accompanying drawings, in which:

Figure 1 represents a side elevation, partly in section, of a fragment of a wheel with my invention applied thereto.

Figure 2 is a plan view of my invention 40 detached, as indicated by the line 2-2 of Figure 3.

Figure 3 is a vertical transverse sectional view on the line 3-3 of Figure 1.

Figure 4 is a view similar to Figure 1, but 45 showing the wheel in a different position.

Figure 5 is a plan view of the flanged member, which is attached to the periphery of the wheel.

Figure 6 is a plan view of the lag member 50 detached, and

Figure 7 is a vertical sectional view on the line 7-7 of Figure 2.

Referring now specifically to the drawings, the numeral 10 indicates the flanged 55 member which is attached to the periphery

of the wheel 11 by means of the bolts 12. This member 10 has two teeth 13, extending the full width of the wheel tread and projecting radially therefrom. The teeth are spaced from each other to form a channel 60 14, and are connected by a web through which the bolts 12 are secured. The outer surfaces of the teeth are curved, as shown at 15. The profile of this curved surface, as viewed from the side of the wheel, is a true 65 involute curve struck from the periphery of the wheel as an evolute. Extending laterally from the member 10 are flanges 16, which are continued inwardly to the periphery of the wheel, and form a continuation, 70 as shown at 17 of the curved surface 15. The lag member 18 is rectangular in shape, and formed with a rectangular opening 75 which receives the toothed member, the forward and rearward surfaces 19 of the opening being shaped to conform to the curved surfaces 15 of the toothed member. The involute surface 15 cooperates with the rolling contacting surfaces of the lag and the periphery of the wheel. There is no relative 80 sliding between the lag and the periphery of the wheel, due to the involute construction, but there is instead a perfect rolling contact.

The member 18 also has the lugs 20 extending inwardly from the sides of the opening above the flanges 16, whereby the lag member is retained on the toothed member in position for the latter to roll thereon as the tractor moves along the ground. The 85 under surfaces of the lugs 20 are curved, as shown at 21, so as to permit an easy rolling action between the two members. The lag members are provided with spurs 22, which project into the ground and secure a firm 90 grip therein, as will be readily understood.

It will be understood that in attaching this device to a wheel, the member 10 must first be inserted in the member 18, with the lugs 20 engaging the flanges 16. The bolts 100 12 are then secured rigidly to the wheel. The operation of my invention will be clearly seen from Figures 1 and 4. As the tractor moves over the ground, the spurs 22 engage therein, and the toothed members 10 105 roll in the shoes 18. Since the contacting surfaces are in the form of a true involute curve, the rolling action will operate on the same principle as a gear tooth, which is made in the same manner. Thus there will 110

be no backlash as is found in the former devices for this purpose.

After the bearing surface becomes worn, the shoes may be reversed, thus doubling the life of the shoe. There will be no wear at all on the tire or rim of the wheel, and when the device is worn out it may be replaced at comparatively little expense.

I claim as my invention:

- 10 1. In a device of the character described, a bearing member having means for securely attaching the same to the outer periphery of a wheel, flanges projecting laterally therefrom, and a lag member having lugs loosely engaging said flanges to retain said lag member in supporting relation to the bearing member.
- 15 2. In a device of the character described, a bearing member having means for securely attaching the same to the outer periphery of a wheel, the front and rear faces of said member forming curved bearing surfaces, flanges formed on the sides of said member, and a lag member having lugs extending over said flanges to retain said lag member in position to engage the bearing surfaces as the wheel revolves.
- 20 3. In a device of the character described, a bearing member having means for securely attaching the same to the outer periphery of a wheel, the front and rear faces of said member forming convexly curved bearing surfaces, the profile of each of said curved surfaces being an involute curve, flanges
- 25 projecting laterally therefrom, and a lag member having lugs loosely engaging said

flanges to retain said lag member in supporting relation to the bearing member.

4. In a device of the character described, a bearing member having means for securely attaching the same to the outer periphery of a wheel, flanges projecting laterally therefrom, and a lag member having lugs in rolling contact with the upper surface of the flanges whereby said lag member is supported in position to engage the bearing member.

5. In a device of the character described, a bearing member having means for securely attaching the same to the rim of a wheel, flanges extending laterally from said bearing member and spaced from said rim, a tooth extending outwardly from said bearing member and having an involute face, and a lag member having a transverse portion in engagement with said involute face and having lugs extending inwardly and positioned between said rim and flanges.

6. The combination with a wheel rim, of means secured to the outer periphery of the rim and having tooth portions, a socketed shoe member loosely carried by the means for rocking inter-engaging tooth and socket co-action therewith, the rocking movements of the shoe member being transverse to the wheel axis.

In testimony that I claim the foregoing I have hereunto set my hand at Clintonville, in the county of Waupaca and State of Wisconsin.

HAROLD G. BOWKER.
